UNITED STATES PATENT OFFICE.

CHARLES JOEL WOLFE, OF HUMMELSTOWN, PENNSYLVANIA.

OPENER.

Application filed October 8, 1925. Serial No. 61,240.

This invention relates to bottle and jar openers and aims to provide novel means whereby the usual mustard jar, pickle jar or the like may be opened eliminating any possibility of the bottle or jar becoming broken.

Another object of the invention is to provide a device of this character including a prong designed to pierce the cover or closure, should it be desired to open a jar or bottle, wherein it is necessary to relieve the vacuum to facilitate the opening thereof.

A still further object of the invention is the provision of an opening so constructed that it may be adapted for use in connection with jars or bottles of various sizes.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a plan view of an opener constructed in accordance with the invention.

Figure 2 is a sectional view taken on line 2-2 of Figure 1.

Figure 3 is a sectional view taken on line 3-3 of Figure 1.

Referring to the drawing in detail, the reference character 5 indicates the body portion of the device, which is relatively broad the same tapering off to provide a handle 6, that is provided with an opening 7 whereby the device may be positioned over a supporting hook or the like.

Stamped from the body portion is a finger 8 that is inclined forwardly and provided with a pointed extremity 9 disposed at right angles to the body of the finger defining a shoulder 10.

Extending from the body portion and dis-

posed in a direction opposite to the finger 8 is a substantially long finger 11, which also inclines forwardly and is provided with a pointed extremity 12 defining a shoulder 13. Thus it will be seen that due to this construction, the device may be fitted over the cap of various sized bottles or jars.

These fingers 8 and 11 are arranged in spaced relation with the forward end of the body portion so that the forward end of the body portion may rest on the top of the cover or closure to permit a prying action.

The reference character 14 indicates a spur or prong adapted to pierce the cover providing an opening to relieve the vacuum within the bottle or jar being opened to permit the cover to be readily removed.

As shown by Figure 2, the device is positioned over the cover or closure to be removed in such a way that the finger will engage the cover, the shoulder of the finger contacting with the cover which is indicated at A. Upon an upward movement of the handle portion 6, the cover will be lifted from the bottle or jar, the opener in no way touching the glass of which the bottle or jar is formed to chip or break the same.

The outer end of the body portion is tapered as at 15 to permit the device to be used in prying open cans with pressed in lids.

I claim:

A can opener including a body portion embodying a handle portion and a substantially wide portion, a prong stamped from the wide portion, a finger stamped from the wide portion and extending from the wide portion in the same direction as the prong, said finger being longer than the prong and disposed in spaced relation with the prong and the free end of the finger being bent towards the prong to provide a hook.

In testimony that I claim the foregoing as my own, I have hereto affixed my signature.

CHARLES JOEL WOLFE.
